DESIGN FOR A TRIPOD

Everett Warren Billings, Jr., Los Angeles, Calif.

Application April 9, 1946, Serial No. 128,411

Term of patent 14 years

(Cl. D57—1)

To all whom it may concern:

Be it known that I, Everett Warren Billings, Jr., a citizen of the United States, residing at Los Angeles, county of Los Angeles, and State of California, have invented a new, original, and ornamental Design for a Tripod, of which the following is a specification, reference being had to the accompanying drawing, forming part thereof.

The figure is a perspective side view of a tripod showing my new design.

I claim:

The ornamental design for a tripod, substantially as shown.

EVERETT WARREN BILLINGS, JR.
